FIG. 1 is a top plan view showing the interior fluid containing portion of the humidifier reservoir of our new design;

FIG. 2 is a bottom plan view thereof;

FIG. 3 is a side elevational view thereof on a reduced scale;

FIG. 4 is an opposite side elevational view thereof on a reduced scale;

FIGS. 5 and 6 are respectively left and right end elevational views of FIG. 3 drawn on the scale of FIG. 1;

FIGS. 7 and 8 are cross-sectional views taken along lines 7-7 and 8-8, respectively, of FIG. 1;

FIG. 9 is a fragmentary bottom plan view of a second embodiment differing from the first only by the installation of snap-in viewing windows on opposite sides of the reservoir;

FIGS. 10 and 11 are respectively fragmentary right and left side elevational views thereof;

FIG. 12 is an enlarged cross-sectional view taken on line 12-12 of FIG. 9.

FIGS. 9, 10 and 11 are fragmentarily shown for convenience of illustration.

We claim:

The ornamental design for a humidifier reservoir, as shown and described.
